UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,317,074.

Specification of Letters Patent. Patented Sept. 23, 1919.

Application filed August 30, 1916. Serial No. 117,623.

To all whom it may concern:

Be it known that I, HENRY P. CLAUSEN, a citizen of the United States, residing at Mount Vernon, in the county of Westchester 5 and State of New York, have invented certain new and useful Improvements in Telephone Systems, of which the following is a full, clear, concise, and exact description.

The present invention relates to telephone 10 lines of the type employing machine switches.

It is frequently desirable, when a subscriber leaves his substation, that calls intended for this substation be diverted to another telephone station where the call will 15 receive attention.

The main feature of this invention, therefore, is a circuit arrangement whereby a call intended for one substation will actuate a 20 call signal at another substation where certain information may be given to the calling party.

Referring to the drawings: Figure 1 represents diagrammatically a portion of a 25 telephone system employing the present invention; the dotted rectangles shown in this figure represent diagrammatically connectors, the circuit arrangement of which is shown in Fig. 3. Fig. 2 illustrates diagrammatically a portion of a telephone system 30 employing a modified form of the present invention. In this diagram also, the dotted rectangle represents a connector. Fig. 3 shows a suitable circuit arrangement for operating the connectors which are employed 35 in this system.

The form of invention disclosed in Fig. 1 is particularly adapted to the use of a subscriber who has two telephones, one of which 40 is located at his office and the other at his residence. With the present invention, it will be possible for the subscriber on leaving his office to set up a circuit by which the line signals of both of his telephones will be operated when a call comes to the telephone at 45 his office.

Referring to Fig. 1, 5 designates the usual substation apparatus which may be located at the office of the subscriber. When the 50 subscriber is about to leave his substation, he will remove his receiver from the hook. This operation causes the brushes 6 and 7 of the finder to engage the contacts 8 and 9 of his line. The subscriber will then transmit, 55 by means of his sending device, impulses cor-

responding to the digits of a previously assigned number, which will set the connector represented in Fig. 1, by the brushes 10 and test brush 11, on the contacts 12 and test contact 13. This operation places ground on 60 test contact 13 and thereby actuates relay 14 over the following circuit: grounded battery, left-hand winding of relay 14 and conductor 15 to grounded contact 13. Relay 14 thereupon attracts its armatures and at its right-hand armature establishes a locking circuit extending from grounded battery, resistance 16, conductor 17, front contact and armature of relay 14, right-hand winding of this relay to ground. Relay 14 at its left-hand armatures establishes a circuit which connects substation 5 with substation 18. This circuit may be traced as follows: substation apparatus 5, conductor 19, front contact and innermost left-hand armature of relay 14, 70 conductor 20, substation apparatus 18, conductor 21, front contact and outermost left-hand armature of relay 14, conductor 22 to substation apparatus 5.

Substation 18 may similarly be connected 80 to sub-station 5 by removing the receiver at substation 5 which causes brushes 23 and 24 of the finder to engage contacts 25 and 26. The subscriber then transmits impulses corresponding to the assigned number, and sets 85 the brushes 27 and test brush 28 of the connector on the contacts 29 and test contact 30. This also places ground on contact 30 which causes relay 14 to be energized over a circuit which may be traced from grounded battery, 90 left-hand winding of relay 14, conductor 15, conductor 31 to grounded contact 30. Relay 14 thereupon attracts its armatures, as above described, and also completes a locking circuit through its right-hand winding. When 95 it is desired to sever the connection between substations 5 and 18, the subscriber located at either of these stations will transmit impulses corresponding to the digits of another previously assigned number which will 100 place the brushes of the connector, in the case of the connector associated with substation 18, on to contacts 32 and test contact 33. This will establish a shunt circuit about the relay 14, which shunt circuit may be 105 traced from grounded battery, resistance 16, conductor 34, to grounded test contact 33. Similarly from substation 5: the brushes of the connector may be directly set upon the contacts 35 and test contact 36, which will 110

likewise establish a shunt circuit about the locking winding of relay 14.

With the left-hand armatures of relay 14 in their attracted position, when a calling line L is extended by means of switches represented by switch brushes 37, 38 and 39 to the contacts corresponding to the line connected with sub-station 5, the application of ringing current to this line will actuate the ringing devices at both of the sub-stations 5 and 18.

Referring to Fig. 2, in this arrangement, when the subscriber whose substation is indicated at 50 is about to leave his office, he may dial a previously assigned number which will connect him to a special operator at the telephone exchange. After having dialed this number by sending additional impulses, he will actuate an auxiliary switch which will complete circuits for operating various signals at the exchange. These signals will inform the operator of his whereabouts or when he will return to his office.

When the subscriber at substation 50 removes his receiver from its switchhook, the brushes 51 and 52 of the finder will locate the contacts 53 and 54 of this calling line. The subscriber then operates his dial switch to send impulses corresponding to the digits of a previously assigned special number which set the brushes 55, 56 and 57 on to contacts 58 and 59 and "dead" contact 60. Relay 61 is thereupon actuated over a circuit which may be traced from grounded battery, left-hand winding of relay 61, contacts 59, the link circuits previously established through the substation 50, upper side of the line to contact 58, normally closed contact 62, right-hand winding of relay 61 to ground. Relay 61 attracts its armature and completes an energizing circuit for the slow-releasing relay 63 which extends from grounded battery, relay 63, front contact and armature of relay 61 to ground. When the subscriber operates his dial to send additional impulses corresponding to the various signals at the exchange, the armature of relay 61 will be momentarily retracted. This completes an energizing circuit for the slow-releasing magnet 64, which circuit extends from grounded battery, relay 64, front contact and armature of relay 63, back contact and armature of relay 61 to ground. Relay 64 attracts its left-hand armature and establishes a maintaining circuit about the normally closed contact 62 the purpose of which will be herein later described. At the same time that relay 63 attracted its armature, an energizing circuit for the motor magnet 65 of the auxiliary switch, was established which extends from grounded battery, magnet 65, conductor 66, armature and front contact of relay 63, armature and back contact of relay 61 to

ground. In response to the additional impulses sent, motor magnet 65 operates the auxiliary switch brush 67 to engage the various contacts 90, which in turn closes a break-point in the energizing circuit of the lamp signals 68, 69, 70, 71 and 72. The maintaining circuit established about the off-normal contact 62 is provided to prevent any further actuation of the motor magnet when the switch has moved to an off-normal position.

In this arrangement, when a call is extended from the line L' by means of the connecting switch brushes 73, 74 and 75 to the substation 50, the application of ringing current to this line will momentarily energize relay 76. When relay 76 is energized, it attracts its armature and completes a locking circuit which extends from grounded battery, through one of the lamp signals, for example, lamp 68, conductor 77, contact 90, switch brush 67, armature and front contact of relay 76, contact 78, contact member 79 to ground. The operator located at the exchange notes the actuation of signal 68 and inserts a plug (not shown) into a jack 80. This causes arm 81 to move contact member 79 out of engagement with contact 78, whereupon the energizing circuit for lamp 68 is interrupted. The operator then informs the calling party of the information indicated by the lamp signal 68 and when the subscriber returns to his office, he may call up and learn if the operator has answered any calls directed to his office.

The subscriber at substation 50 may "wipe out" these connections in the following manner: when he removes his receiver from the switchhook at substation 50, brushes 51 and 52 will engage the contacts 53 and 54 corresponding to his line; he will then transmit impulses corresponding to a number previously assigned for the purpose of wiping out the connection. This will set brushes 82, 83 and 84 on the contacts 85, 86 and 87. This places ground on contact 87, and release magnet 88 receives an energizing impulse over a circuit extending from grounded battery, release magnet 88, contact 87. Release magnet 88 attracts its armature and completes a locking circuit which is maintained until the switches are restored to normal position. This circuit extends from grounded battery, relay 88, front contact and armature of relay 88 off-normal contact 89 to ground. The operator located at the exchange is provided with a key 99 with which she may also wipe out or restore the switches to normal position. In this instance, the energizing impulse for release magnet 88 will be received over a circuit extending from grounded battery, release magnet 88, and key 99 to ground.

The circuits employed in establishing the various link connections of the present in-

vention may be of any preferred form. The circuits for operating the final or connector switch are disclosed in Fig. 3 and will be hereinafter described.

- 5 When the link circuits of the system disclosed in Figs. 1 and 2 have been extended to the connectors by means of the line and selector switches, the stepping relay 100 of the connector is energized over a circuit which may be traced from grounded battery, left-hand winding of relay 100, upper side of the line, through the link circuits, over the lower side of the line, right-hand winding of relay 100 to ground. Stepping relay 100 attracts its armature and thereby completes an energizing circuit for the slow-releasing relay 101. This circuit extends from grounded battery, relay 101, front contact and armature of relay 100 to ground. Relay 101 then attracts its armatures. In response to the operation of the sending device, relay 100 momentarily retracts its armature and completes an energizing circuit for the second slow-releasing relay 102. This circuit extends from grounded battery, relay 102, front contact and armature of relay 101, back contact and armature of relay 100 to ground. Relay 102 then attracts its armatures and completes an energizing circuit for the escape magnet 103, which circuit extends from grounded battery, escape magnet 103, right-hand armature and front contact of relay 102 to ground.
- 35 When the armatures of relay 101 were attracted a break point in the operating circuit of the primary motor magnet 104 was closed. Each time that the armature of relay 100 is retracted, due to the interrupting of its energizing circuit at the sending device, the operating circuit for primary motor magnet 104 is completed. This circuit extends from grounded battery, primary motor magnet 104, side-switch wiper 105 in its first position, conductor 106, front contact and right-hand armature of relay 101, back contact and armature of relay 100 to ground. At the close of the first series of impulses, relay 100 holds its armature attracted for a relatively long interval, thereby interrupting the energizing circuit of second slow-release relay 102 at the back contact and armature of relay 100. Relay 102 deenergizes and interrupts the operating circuit of escape magnet 103 at the front contact and right-hand armature of relay 102. The escape magnet in this instance operates on its deenergization to move the side-switch wipers into the second position.
- 60 The impulse-sending device is then actuated to send impulses corresponding to the units digit of the assigned number, whereupon slow-releasing relay 102 is again energized by reason of the momentary retrac-
- tions of the armature of relay 100. The operating circuit for the secondary magnet, in parallel with this last named circuit, extends from grounded battery, secondary motor magnet 107, side-switch wiper 105 in its second position, conductor 106, front contact and right-hand armature of relay 101, back contact and armature 100 to ground. At the close of the units series of impulses, relay 100 is maintained energized, whereupon the energizing circuit of relay 102 is again interrupted as previously described, and by retracting its armature causes escape-magnet 103 to be deenergized. The side-switch wipers thereupon move into their third position.
- 70 It will be noted that when side-switch wiper 110 moves into its third position, the test contact of the desired set of contacts will be connected to ground.
- 75 If, for any reason, the desired contact cannot be seized due to the presence of ground on its test contact, a circuit for the releasing magnet 108 will be completed which may be traced from grounded battery, 80 magnet 108, off-normal contact 109, left-hand armature and back contact of slow-releasing relay 102, side-switch wiper 110 in its second position, conductor 113, to ground.
- 85 When this connecting circuit arrangement is employed in the system disclosed in Fig. 2, after the brushes of the connector have been set upon the desired set of terminals, line relay 100 remains energized. At its 90 front contact and innermost armature an energizing circuit is completed for slow-releasing relay 101 from grounded battery, front contact and innermost armature to ground. When the subscriber sends the additional impulses, motor magnet 65 places brush 67 in a position to energize the desired signals 68, 69, 70, 71 or 72, as line relay 100 momentarily retracts its outermost right-hand armature, thereby interrupting 95 the operating circuit of relay 61. This circuit may be traced from grounded battery, left-hand winding of relay 61, contact 59, brush 56, lower side of the line, side-switch wiper 111 in its third position, conductor 100 110, front contact and outermost right-hand armature of relay 101, front contact and outermost armature of relay 100, conductor 113, side-switch wiper 114 in its third position, brush 55, contact 58, normally closed contact 62, right-hand winding of relay 61, to ground. In this way the impulses of the calling dial are repeated to control the operating circuits of motor magnet 65.
- 105 The release of the line and selecting 115 switches is accomplished by the calling party replacing his receiver on the switchhook. This operation causes the line relay 100 of the connector to deenergize and to retract its armature. The energizing circuit of re- 120 130

lay 101 is interrupted at the front contact and innermost right-hand armature of relay 100. By retracting its armatures the relay 101 completes a release circuit for the connector which may be traced from grounded 5 battery, release magnet 108, off-normal contact 109, back contact and left-hand armature of relay 101, back contact and innermost right-hand armature of relay 101, back contact and innermost right-hand armature of line relay 100, to ground. The 10 release circuits for the preceding selectors and line finder are completed over conductor 115, back contact and outermost right-hand armature of relay 101, innermost armature of relay 100, to ground.

What is claimed is:

1. In a telephone system, a primary telephone station provided with a call signal, 20 a secondary telephone station provided with a call signal, a telephone line, means for extending said line to said stations, means including automatic switching means for interrelating the call signals of said stations, 25 and means for restoring said switching means to normal position.

2. In a telephone system, a primary telephone station and a secondary telephone station each provided with a call signal, a telephone line, means for extending said line to said primary and said secondary stations, an automatic switching device, an operating 30 circuit for the call signal at said secondary telephone station controlled in part by said automatic switching device, whereby said signals are simultaneously actuated, and means for opening said circuit.

3. In a telephone system, a primary substation, a secondary substation, telephone 40 lines leading to said substations, automatic switching means, means controlled through said automatic switching means for connecting said substations in multiple to said lines prior to the initiation of a call to said substations.

4. In a telephone system, a central station, a plurality of substations connected therewith, and means at the central station controlled by a subscriber at one substation for 50 immediately diverting a call intended for said substation to another substation.

5. In a telephone system, a primary substation, a secondary substation, telephone lines leading to said substations, a telephone 55 line individual to, and connecting said primary substation and said secondary substation, said last-mentioned line having a normally open contact therein, automatic switching means, and means controlled through said automatic switching means for closing said contact.

6. In a telephone system, a primary substation, a secondary substation, telephone lines leading to said substations, a telephone 65 line individual to, and connecting said pri-

mary substation and said secondary substation, said last-mentioned line having a normally open contact therein, electromagnetic means for closing said contact and selectively operated automatic switching means 70 for operating said electromagnetic means.

7. In a telephone system, a primary telephone station provided with a call signal, a secondary telephone station provided with a call signal, a telephone line, means for extending said line to said telephone stations as called stations, means including automatic switching means for interrelating the call signals of said stations, and means for restoring said switching means to normal position.

8. In a telephone system, a primary station and a secondary station, each provided with a call signal, a telephone line, means for extending said line to said primary and said secondary telephone stations as called stations, an automatic switching device, an operating circuit for the call signal at said secondary telephone substation controlled in part by said automatic switching device whereby said signals are simultaneously actuated, and means for opening said circuit.

9. In a telephone system, a primary substation, a secondary substation, telephone lines leading to said stations, automatic 95 switching means, means controlled by one of said stations through said automatic switching means for simultaneously connecting said substations in multiple to said lines.

10. In a telephone system, a primary substation, a secondary substation, telephone lines leading to said substations, and means for connecting said substations in multiple to said lines prior to the initiation of a call to said substations.

11. In a telephone system, a telephone exchange, a plurality of telephone stations associated therewith, and means controlled from one of said telephone stations for immediately diverting a call from said last mentioned telephone station to another telephone station.

12. In a telephone system, a telephone exchange, a plurality of telephone stations associated therewith, and means controlled from one of said telephone stations for diverting a call from said last mentioned telephone station to another telephone station prior to the initiation of said call.

13. In a telephone system, an exchange, 120 a plurality of telephone stations associated therewith, and automatic means controlled from one of said telephone stations for immediately diverting a call from said last mentioned station to another telephone station.

14. In a telephone system, an exchange, a plurality of telephone stations associated therewith, and directly operable means controlled from one of said telephone sta- 130

tions for immediately diverting a call from said last mentioned station to another telephone station.

15. In a telephone system, an exchange, a plurality of telephone stations associated therewith, and directively operable means controlled from one of said telephone stations for diverting a call from said last mentioned station to another telephone station

10 prior to the initiation of said call.

16. In a telephone system, a primary sub-

station, a secondary substation, telephone lines leading to said substations, and means controllable from one of said substations for connecting said substations in multiple to 15 said lines prior to the initiation of a call to said substations.

In witness whereof I hereunto subscribe my name this 28th day of August, A. D. 1916.

HENRY P. CLAUSEN.
